UNITED STATES PATENT OFFICE.

JAMES PERCIVAL ROSS, OF GIRVIN, SASKATCHEWAN, CANADA.

SHEET-MUSIC TURNER.

Application filed July 10, 1922. Serial No. 573,887.

To all whom it may concern:

Be it known that I, JAMES P. Ross, a subject of the King of Great Britain, residing at Girvin, in the Province of Saskatchewan and Dominion of Canada, have invented new and useful Improvements in Sheet-Music Turners, of which the following is a specification.

This invention relates to a music leaf 10 turner, the general object of the invention being to provide an attachment for a piano or the like for turning the leaves of sheet music, the device being operated by the knee or hand of the player, to turn the 15 sheets one by one without the necessity of raising the hands from the key-board.

Another object of the invention is to provide means whereby a sheet can be easily turned back, when it is desired to repeat the music, without interfering with the 20 operation of the device.

A still further object of the invention is to provide adjustable clamps on the arms of the device for engaging the leaves.

This invention also consists in certain other features of construction and in the combination and arrangement of the several parts, to be hereinafter fully described, illustrated in the accompanying drawings 30 and specifically pointed out in the appended claims.

In describing my invention in detail, reference will be had to the accompanying drawings wherein like characters denote like or corresponding parts throughout the several views, and in which:—

Figure 1 is a front view showing a part of the piano with my invention in use.

Figure 2 is a top plan view of the parts 40 shown in Figure 1.

Figure 3 is a longitudinal sectional view through the device.

Figure 4 is a front elevation with parts in section and parts broken away, showing 45 the arms turned to the right.

Figure 5 is a view similar to Figure 4 but showing one arm turned to the left.

Figure 6 is an end view.

Figure 7 is a section on line 7—7 of 50 Figure 4.

Figure 8 is a section on line 8—8 of Figure 4.

Figure 9 is a section on line 9—9 of Figure 4.

Figure 10 is an edge view of one of the 55 clamps.

In these views 1 indicates a casing which is adjustably secured to the end pieces 2, these end pieces being provided with hook-shaped upper ends 3 for engaging the front 60 board A of the piano. These parts are so formed that they will be in a position to hold the sheet music where it can be readily seen by a person playing the piano. The end pieces carry the spring clamping 65 fingers 4 for holding the sheet music in place and the casing is provided with a depending arm 5 which is detachably secured to the lower edge of the casing and is used when the device is to be used for turning 70 the leaf of a book. This arm is adapted to hold the center of the book in raised position. A number of pinions 6 are rotatably mounted on a rod 7 which passes through the center of the casing and each 75 pinion carries an arm 8 upon which the leaf holders 9 are adjustably mounted by having their eyes 10 engaging the arms. These arms and eyes are preferably of square formation to prevent turning movement of the 80 holders on the arms. Each pinion is engaged by a rack bar 11, slidably mounted in the casing, and these bars are adapted to be moved by an L-shaped member 12 which is slidably mounted in the casing and has its upper end projecting through a slot in the casing, this upper end acting as a finger hold for moving the parts to their normal position. The front part of this member 85 is formed with rack teeth, as shown at 13, and these teeth are engaged by a spring 90 pressed dog 14 which is pivotally mounted to a rocking lever 15, the upper end of which is guided by the plate 16 forming part of the casing. A spring 17 normally holds the 95 rocking lever against a stop pin 18 in the casing and a cable 19 has one end connected with the said lever and its other end is connected with one crank of a crank rod 20 mounted below the key-board of the piano 100 and which has its other crank connected by a link 21 with an operating lever 22 which is pivoted to a bracket 23 on the under side of the key-board support of the piano. Thus this lever 22 can be operated by the 10 knee of the player or by his hand. The upper rack bars 11 are provided with notches 24 for engaging pins 25 on the upright arm of the member 12. The notch in the upper bar is smaller than that in the second bar so that the pin 25 will not engage the front wall of the notch 24 of the

- second bar until the member 12 has been moved to a considerable extent. Pins 26 are placed in the casing and springs 27 are located therein for pressing the rack bars 11 downwardly upon the pins. The upper rack bars are each provided with a tooth 27' for engaging the pins 26, when the rack bar has been moved forwardly so as to raise the rack bars and thus free the notches 24 5 from the pins 25.
- From the foregoing it will be seen that when the lever 22 is moved to the left by the knee or hand of the operator, the cable, which passes over suitable guiding pulleys 15, will move the rocking lever 15 forwardly against the action of its spring, thus causing the dog 14 to engage the rack teeth 13 to move the member 12 towards the right. This movement of member 12 will move the 20 upper rack bar 11 due to the fact of the pin 25 engaging the notch 24 of said rack bar and the teeth engaging the pinions 6 will rotate the pinions and thus swing the arm 8 attached thereto over to the left and 25 so turn the page to which the arm is connected by its holder. Just before the completion of the movement of the parts the tooth 27 on the top bar 11 will engage the pin 26 so that the bar will be raised and 30 thus move the notched part away from the pin 25. During this operation the second pin 25 will have moved forwardly in the notch 24 of the second bar 11 to a point adjacent the inner wall of the notch so that 35 when the lever 22 is moved again to cause the member 12 to continue its forward movement, said second pin 25 will engage the front wall of the notch of the second bar 11 and move this bar forwardly, thus rotating 40 the second pinion and swinging the second arm 8 towards the left so as to turn the second sheet. The tooth 27' of this second bar 11 will engage the pin 26 so that this second bar 11 is freed from the pin 25 in 45 order to permit the member 12 to again be moved forwardly without moving the two upper bars 11. When the lever 22 is moved for the third time the upright part of member 12 will strike the third bar 11 to cause 50 it to move forwardly to rotate the pinion and thus swing the third arm 8 to the left to turn the third page. Thus the pages of the sheet music are turned one at a time and when desired by simply pressing the lever 55 22. After turning the page and it is desired

to repeat it is simply necessary to swing the arm 8 back to its original position which will cause the pinion to return the rack bar 11 to its original position and as this bar moves forwardly it will drop down so that 60 its notch will engage the pin 25 and thus the member 12 will be returned to its position. Thus the music on a page can be repeated without interfering with the operation of the device. When all the leaves have 65 been turned the arms will swing back in unison but in this case it will be necessary to return the member 12 back to its original position by means of its projecting upper end. As the lever 22 is operated the member 70 12 is moved forwardly a certain distance and then comes to rest and the dog 14 is returned to its starting point. When the lever 22 is released by means of the spring 17 pulling the rocking lever 15 back 75 against the pin 18, the dog is in a position to engage a new part of the member 12 to move it forward another step to operate the next rack bar. It will be understood that 80 as many sheet holding arms can be used as 85 desired.

It is thought from the foregoing description that the advantages and novel features of my invention will be readily apparent.

I desire it to be understood that I may 85 make changes in the construction and in the combination and arrangement of the several parts, provided that such changes fall within the scope of the appended claim.

What I claim is:—

A leaf turner of the class described comprising a casing, a shaft therein, pinions mounted on the shaft, an arm connected with each pinion, a leaf holder adjustably mounted on each arm, a rack bar for engaging each pinion, an L-shaped member having a rack part thereon, a pawl carrying lever, a pawl thereon engaging the rack part, manually operated means for operating the lever, pins on the L-shaped member engaging notches on the rack bars, said notches being of different lengths, means for freeing the pins from the notches after a certain amount of movement of the parts, such means consisting of projections on the rack bars and stationary stops in the casing for engaging the projections for raising the rack bars.

In testimony whereof I affix my signature.

JAMES PERCIVAL ROSS.
